UNITED STATES PATENT OFFICE.

DEMPSEY L. REEHL, OF NEW BRIGHTON, PENNSYLVANIA.

BRIDGE-LOCKING MECHANISM.

1,145,166.

Specification of Letters Patent.

Patented July 6, 1915.

Application filed February 18, 1915. Serial No. 9,019.

To all whom it may concern:

Be it known that I, DEMPSEY L. REEHL, a citizen of the United States, and resident of New Brighton, in the county of Beaver and State of Pennsylvania, have invented certain new and useful Improvements in Bridge-Locking Mechanism, of which the following is a specification.

My invention relates to the construction of locking mechanism for draw bridges, and more particularly relates to the construction of the mechanism employed in supporting and fastening the ends of such bridges in closed position relative to the approaches of the bridges to prevent movement of the bridges when in closed position, and a rail key for spanning the gap between the approaches and the movable spans, thereby maintaining a continuous rail.

One object of my invention is to provide a bridge locking mechanism having novel means whereby the bridge is secured in closed position and whereby the locking mechanism is actuated in locking and releasing the bridge.

Another object of the invention is to provide a bridge locking mechanism having improved means whereby the ends of a draw bridge are supported and are locked in closed position.

A further object of this invention is to provide a bridge locking mechanism having novel means whereby the track rails are made continuous and by which the rail keys and locking bars and, when used, the supporting wedges, are actuated in fastening and releasing the bridge.

A still further object of this invention is to provide a bridge locking mechanism having novel means by which the several parts of the locking mechanism are actuated in pre-determined order in fastening and releasing the bridge.

Still further objects of my invention will become apparent as it is more fully described hereinafter and pointed out in the appended claims.

Referring now to the drawings forming part of this specification, Figure 1 is a plan showing one end of a draw bridge as fastened in closed position relative to the abutting bridge approach, with a lock and lock actuating mechanism, constructed and arranged in accordance with my invention.

Fig. 2 is a side elevation of the apparatus shown in Fig. 1. Fig. 3 is a plan, partly

broken away, showing the wedges and locking bars, and actuating mechanism therefor, forming part of my improved apparatus. Fig. 4 is a diagrammatic side elevation showing the rail keys and wedges, and connecting gearing by which the rail keys and wedges are actuated, the rail keys being shown in retracted position. Fig. 5 is a diagrammatic side elevation showing the mechanism illustrated in Fig. 4, the wedges and rail keys being shown in retracted or disengaged position. Fig. 6 is a transverse section, on an enlarged scale, showing the construction of the rail key by which a continuous rail is formed, the rail key extending across the gap between the movable and fixed rails when the bridge is in a closed position. Fig. 7 is a sectional side elevation of the end of the bridge showing the bridge latch and operating connections. Fig. 8 is an end elevation showing the bridge latch as connected to the ends of the bridge. Fig. 9 is a diagrammatic side elevation showing the mechanism illustrated in Fig. 4, the wedge mechanism being omitted to show the bridge lock, the rail keys and bridge lock being shown in retracted or disengaged position. Fig. 10 is a plan showing the engaging wedging faces of the wedges and shoes therefor, by which the ends of the bridge are moved laterally when necessary, into locking position. Fig. 11 is an end elevation, partly in section, showing details in the construction of the wedge and shoes of Fig. 10.

In the accompanying drawings, the numeral 2 designates one end of a draw bridge which is supported in the middle of its length on a suitable foundation or pier, and which is arranged to swing or rotate at the middle of the length of the bridge about a vertical axis. The construction of this middle support not forming part of this invention is not shown or described in detail.

The end 2 of the bridge is shown in closed position opposite one of the bridge approaches 3. The bridge shown is a railroad bridge provided with parallel track rails 4, 4, which are laid on wooden ties 5, 5, in the usual known manner, with the ends of the ties connected together at each side of the bridge by longitudinal wooden stringers or guard rails 6, 6. The track rails 7, 7, on the abutments or approaches 3 are spiked or otherwise fastened to ties 8 so as to align with the track rails 4, 4, these also being

connected at their ends by longitudinal stringers or guard rails 9. The ties 5 of the bridge 2 are secured upon lengthwise parallel girders 10, 10, which extend lengthwise from one to the other of the approaches 3, 3, which are located on opposite sides of the space spanned by the bridge, and transverse girders 11 connected to the ends of the girders 10, are framed into or fastened to bridge trusses 12, 12, which extend lengthwise parallel with the girders 10, 10, (see Fig. 3). One side of the head of the track rails 4, 4, is cut away for a short distance inward from the end of each of these rails, and the heads of the rails 7, 7, at the abutting ends of the track rails on the bridge approaches 3, are cut away for a short distance in a similar manner.

The abutting ends of the rails 4 and 7 are seated in rail chairs 13 and 14 which are bolted respectively to the ties 5 at the ends of the swinging bridge span and to ties 8 at the abutting ends of the bridge approaches 3. Mounted in the grooves 15 formed in the upper faces of these chairs, on the cut-away side of the heads of the rails 4, the rails forming one side of the grooves, are horizontally extending, lengthwise reciprocating rail keys 16. The rail keys 16, (as will be seen by reference to Fig. 6) have a projecting lug 17 on one side which extends into the under-cut groove formed by the sloping under face 18 of the rail head and the face 19 forming the bottom of the groove 15, so as to prevent vertical lifting movement of the sliding rail keys 16 in the grooves or seats 15. Each of the two rail keys 16 is pivotally connected at one end by a link 20 to the swinging end of a bent rocking arm or lever 21, and the levers 21 are keyed or otherwise fastened by one end to the horizontal rocking shaft 22. The shaft 22 is mounted in bearings 23, 23, which are fastened to the under side of the stringers or guard rails 6, 6, on the ends of the rail ties 5, and one end of the shaft 22 is provided with a forked arm or lever 24 which is pivotally connected by a link 25 to the swinging end of a lever 26 on the gear shaft 27. The shaft 27, which forms part of the lock and wedge actuating mechanism, is made in sections, the sections being connected by any approved form of coupling, and one section of this shaft 27 is mounted in bearings 28, 28, in the gear stand or housing 29 which is secured at its ends to the channel beams 30 extending between and framed to the bridge girders 10, 10. The outer end of the shaft 27, to which the forked lever 26 is secured, is mounted in a bearing 31 on the bracket 32 which is conveniently fastened on one side of the web of one bridge girder 10.

Beneath the ends of the transverse girders 11 and bridge trusses 12 are wedging shoes

33, 33, which are secured to the bottom flanges of the trusses and girders, and secured on a foundation 34 forming part of the approach 3 below the shoes 33, are chairs or bearing stands 35 which are positioned to clear the reciprocating wedges 36 movably secured to the shoes 33, when these wedges are withdrawn into disengaged or retracted position. The wedges 36 are movably mounted to slide on the lower face of the shoes 33, and when in advanced or operative position engage the opposite faces of the shoes 33 and bearing stands or chairs 35, and wedge the ends 2 of the bridge in position, so any vertically downward movement or deflection of the ends of the bridge is avoided when the bridge is locked in closed position. The wedges 36 are pivotally connected by adjustable links 37 to the swinging ends of rocking arms 38. The links 37 are made in sections, and the abutting screw threaded ends of the link sections are connected by a sleeve nut 39 which permits the links being adjusted to length. The rocking arms 38 are secured to shafts 40, of which there are two, which are mounted in suspended bearings 41, 41, fastened to the bearing plates 42 framed to the trusses 12, 12, of the bridge structure.

Beneath one end of the transverse girder 11, adjacent to one of the wedge guides 33 is a reciprocating bridge locking bar 80 which is mounted in a bearing 82 fastened to the bottom flange of the girder 11, and secured to a channel 84 or other means forming part of the approach 3, is a socket or keeper 83 having an opening or hole into which the end of the locking bar 80 extends when in bridge locking position. The bar 80, when extended into the socket 83, holds the bridge in closed position and overcomes any tendency of the end 2 of the bridge to move upward, due to an unbalanced condition of the bridge on its pivot or main pinions. The locking bar 80 is pivotally connected by an adjustable link 87 to the swinging end of the rocking arm 88, and the rocking arm 88 is keyed or otherwise secured on the shaft 40 at one side of the bridge.

Rocking levers or arms 43 keyed to the shafts 40, are pivotally connected at their swinging outer ends by links 44 to the outer swinging ends of the arms 45 on the end sections of the rocking shaft 46, and the shaft 46 is mounted at its ends in pairs of bearings 47 fastened to the bearing plates 42, 42, provided on each of the bridge trusses 12. Owing to its length the shaft 46 is made in sections, and the adjacent ends of the shaft sections are connected by couplings 48 of any approved design. The shaft 46 also is provided with bearings 49, 49, which are fastened to the webs of the bridge girders 10, 10, and with bearings 50, 50, in the bearing stand or housing 29.

Secured on the shaft 46 between the bearings 59, 50, in the housing 29, is an intermittent gear 51 having five teeth on its periphery, with a cusp 52 on each side of the teeth. The teeth of this gear mesh with the six teeth on the periphery of the intermittent gear 53 on the countershaft 54, and the overhanging end of the shaft 54 is provided with a spur gear 55 which meshes with a spur pinion 56 on the worm wheel shaft 57. Mounted on the shaft 27 is an intermittent gear 58 having two cusps 59, 59, and a series of five teeth, the teeth of this gear meshing also with the teeth in the gear 53 on the shaft 54. The worm wheel 60 on the shaft 57 meshes with the worm 61 on the end of the sectional shaft 62, and this worm wheel shaft extends lengthwise parallel with the length of the bridge span from each end of the bridge toward the pivotal center of the bridge. The worm shafts 62 are connected in any desired manner to a suitable driving motor or other prime mover (not shown).

The sectional shaft 46 is provided at an intermediate point in its length with a lever arm 63 which is pivotally connected at its swinging outer end by a link 64 to a lever arm 65 which is mounted on one end of a horizontal shaft 66. The shaft 66 is mounted in bearings 66 secured to the web of the girders 19, 10, and keyed on the shaft 66 in the middle of the length of the shaft is an arm 67 and a double counterweight lever 68 which is arranged to swing freely on the shaft. The rear end of the lever 68 is provided with an adjustable counterweight 69 and the front end of this lever is provided with slots 70 which engage with the pin 71 in the angle connections 72 fixed to the vertically movable latch bar 73. The latch bar 73 extends vertically through guide openings in plates 74 at the top and bottom of the bridge structure, and on its lower end is an anti-friction roller 75. The lever or arm 67 is positioned on the shaft 66 so that when the rail keys 16 are in retracted or open position the swinging end of the lever 67 will engage with the pivoted latch or pawl 76 which is fastened to one side of the latch bar 73 by angle brackets 77.

The bridge being locked in closed position, (the position shown in Figs. 1, 2, 3, 7 and 8) the operation of my improved locking mechanism is as follows: The motor for actuating the locking mechanism is started, and the shaft 62 and worm 61 are caused to rotate, thereby turning the worm wheel 60 and worm wheel shaft 57 in a clockwise direction. When rotated in this direction, the shaft 57, through the meshing spur pinion 56 and spur wheel 55, turns the shaft 54 in a counter-clockwise direction, and the teeth in the intermittent gear 53 engage with the teeth in the intermittent gear 58 and turn this gear so as to rock the shaft 27 and lever

26 keyed thereon to move the lever 24 and bent lever 21 from the position shown on Fig. 2 into that shown in Fig. 4, in which position the rail keys 16 are in disengaged or retracted position. Continued rotation of the shaft 57 in a clockwise direction then brings the teeth in the gear 53 into engagement with the teeth in the intermittent gear 51 on the shaft 46, and turns the gear 51 and shaft 46 in a clockwise direction. This movement of the shaft 46, through the medium of the levers 45, links 44 and levers 43 on the shafts 40, and through the levers 38 and links 37, moves the wedges 36 from the closed or wedging position of Fig. 4 into the disengaged or retracted position shown in Fig. 5. Simultaneously with the movement of the wedge the shaft 46 through the lever 88 and link 87 moves the locking bar 80 from the closed or locking position of Fig. 4 into the disengaged or retracted position shown in Fig. 9.

It will be noted that in retracting the rail keys 16, wedges 36 and locking bars 80, as has been described, the rail keys are fully withdrawn before the commencement of any movement of the wedges 36 and locking bars 80, as while the rail keys 16 are moving, the teeth in the gear 53 are in engagement with the teeth in the rail key actuating gear 58, and the cylindrical face portion of the periphery of the gear 53 is sliding in a cusp 52 in the wedge actuating gear 51. After the rail keys 16 are withdrawn in this manner the teeth in the gear 53 then engage the teeth in the wedge and locking bar actuating gear 51, and during such engagement the cylindrical face portion of the periphery of the gear 53 slides in a cusp 59 in the face of the intermittent gear 58 so that there is no movement of the rail keys 16 while the wedges 36 and locking bar 80 are being moved backwardly into disengaged position.

As the shaft 46 is moved in a clockwise direction to retract or withdraw the wedges 36 and locking bar 80 preparatory to opening the bridge, the lever 63, link 64, lever 65, and shaft 66, will lift the lever 67 until it engages the latch or pawl 76 and thereby raises the latch bar 73 until the lever 67 and pawl 76 are nearly in a straight line between their respective shaft centers. The latch will be maintained in this position so as to hold the roller 75 in lifted position or withdrawn from the locking throat of the latch catch 78 while the bridge is swung into open position. When the bridge swings from the closed position of Figs. 1, 2 and 3, the roller 75 on the lower end of the latch bar 73 will ride up on one or the other of the inclined faces 85 of the latch catch 78, depending upon the direction in which the bridge is swung. As the roller 75 moves over the inclined plane 85 the latch bar 73 is raised sufficiently to allow the pawl 76 to become

disengaged from the lever 67. The pawl 76 then falls by gravity back into a vertical position so as to clear the lever 67, which permits the latch bar 73 to drop by gravity 5 until the stop angle 86 rests on the bottom one of the plates or brackets 74. After the wedges 36 and locking bar 80 are retracted and the latch bar 73 is simultaneously raised, the bridge 2 is swung on its pivot 10 into its open position, and after the required time interval is swung back into closed position. When the bridge, in moving into closed position, reaches a position where the roller 75 on the lower end of the latch bar 15 73 reaches one of the inclined surfaces 79 of the latch catch 78, the latch bar 73 will be raised so as to extend its upper end above its normal position with respect to the floor of the bridge and incidentally show the 20 bridge operator that the bridge is about in closed position. When the closed or nearly closed position of the end of the bridge is reached the latch bar 73 will drop into the latch catch 78 and lock the bridge, indicating that the bridge is in closed position, 25 ready for actuating the wedges or locking bar, and then the rail keys.

The vertically movable latch bar 73 may be omitted when desired and a horizontally 30 reciprocating latch bar constructed like the locking bar 80 substituted therefor, as will be readily understood.

When there is any lateral deflection of the bridge, generally due to unequal expansion, 35 so the track rails 4, 4, and 7, 7, of the bridge 2 and approaches 3 are not in exact alinement, the rails are brought into alinement by means of the lateral wedging faces 90 on the wedges 36, and wedging faces 92 on 40 the locking bar 80, which engage respectively the wedging faces in the guides 91 on the wedge seats 35, and wedging face 93 in the socket 83, as the wedges and rail lock are being moved to closed position. The 45 worm shaft 62 is then rotated by its driving motor in the opposite direction and through the connecting gearing turns the intermittent gear 53 in a clockwise direction. Such movement first turns the gear 51 to move the 50 wedges 36 and locking bar 80 from the position shown in Figs. 5 and 9 into that shown in Fig. 4, without any movement of the gear 58 or rail key 16. After the wedges reach the wedging position shown in Fig. 5, and 55 the locking bar is advanced into the locking position shown in Fig. 9, the gear 51 stops and remains stationary while the gear 53 moves the gear 58 and, through the connecting levers and links, moves the sliding bars 60 16 from the open position shown in Figs. 4 and 5 into the locking position shown in Fig. 2. The above described operations are then repeated as often as necessary at the required intervals in opening and closing

the bridge and in unlocking and locking the 65 bridge in its closed position.

The advantage of my invention will be apparent to those skilled in the art. By the use of my improved bridge locking and wedging mechanism the ends of a draw 70 bridge are securely held in closed position and the locking mechanism is actuated so as to prevent binding of the locking mechanism or deflection of the ends of the bridge by loads passing over the bridge. 75

Modifications in the construction and arrangement of the parts may be made without departing from my invention. Means other than a worm and a worm wheel may be employed to connect the driving motor with 80 the intermittent gears, and means other than a lever mechanism may be employed to connect the intermittent gears to the rails keys, wedges and locking bar actuated by said intermittent gears, means other than intermittent gears may be employed in actuating 85 the bridge locking mechanism, and other changes may be made within the scope of the appended claims.

I claim:—

1. Bridge locking mechanism comprising in combination a draw bridge, a reciprocating rail key, a reciprocating wedge, a reciprocating locking bar, and means for actuating said rail key, wedge, and locking 95 bar, said means being arranged to advance the wedge into wedging position and the locking bar into locking position before moving the rail key into its closed position.

2. Bridge locking mechanism comprising 100 in combination a draw bridge, a reciprocating rail key, a reciprocating locking bar, and means for actuating said rail key and locking bar, said means being arranged to retract the rail key before retracting the 105 locking bar from its bridge locking position.

3. Bridge locking mechanism comprising in combination a draw bridge, a reciprocating rail key, a reciprocating wedge, a reciprocating locking bar, means for actuating 110 said rail keys, wedges, and locking bar, said means being arranged to advance the wedge and locking bar before moving the rail key toward its closed position, and a 115 latch bar arranged to indicate when the closed position of the draw bridge is reached.

4. Bridge locking mechanism comprising 120 in combination a draw bridge span, a reciprocating rail key, a reciprocating wedge, a reciprocating locking bar, and means for actuating said rail key, wedge, and locking bar, said means being arranged to advance the wedge and locking bar before moving 125 the rail key and retract the rail key before retracting the wedge and locking bar.

5. Bridge locking mechanism comprising

in combination a draw bridge, a rail key, a wedge, a locking bar, and means for actuating said rail key, wedge, and locking bar in fastening the bridge in closed position, 5 said means being arranged to actuate the wedge and locking bar in advance of the rail key in locking the bridge in closed position.

6. Bridge locking mechanism comprising in combination a reciprocating rail key, a reciprocating wedge, a reciprocating locking bar, and means for actuating said rail key, wedge, and locking bar in pre-determined order.

15 7. Bridge locking mechanism comprising in combination a reciprocating rail key, a reciprocating locking bar, means for actuating said rail key and locking bar, intermittent gears for actuating said bar actuating means, said gearing being arranged to advance the locking bar into locking position before starting to advance the rail key into locking position, and means for actuating said intermittent gears.

25 8. Bridge locking mechanism comprising in combination a reciprocating rail key, a reciprocating locking bar, lever mechanisms for actuating said rail key and locking bar, intermittent gears for actuating said lever mechanisms, said gearing being arranged to actuate the lever mechanisms to move the locking bar and rail key in pre-determined order in fastening and unfastening the bridge, and means for driving said intermittent gears.

35 9. Bridge locking mechanism comprising in combination a reciprocating rail key, a reciprocating wedge, lever mechanisms for actuating said rail key and wedge, intermittent gears for actuating said lever mechanisms, said gearing being arranged to advance the wedge into wedging position before moving the rail key into closed or rail

locking position, and means for driving said intermittent gears.

45 10. Bridge locking mechanism comprising in combination a reciprocating rail key, a reciprocating wedge, lever mechanisms for actuating said rail key and wedge, intermittent gears for actuating said lever mechanisms, and means for driving the intermittent gears, said gears being arranged to actuate the lever mechanisms to move the wedge and rail key in pre-determined sequence.

55 11. Bridge locking mechanism comprising in combination a reciprocating rail key, a reciprocating wedge, a reciprocating locking bar, lever mechanism for actuating said rail key, wedge, and locking bar, intermittent gears for actuating said lever mechanism, and means for driving the intermittent gears, said gears being arranged to advance the wedge into wedging position and the locking bar into locking position 60 before moving the rail key into its closed position.

65 12. Bridge locking mechanism comprising in combination a reciprocating rail key, a reciprocating wedge, a reciprocating locking bar, lever mechanism for actuating said rail key, wedge, and locking bar, intermittent gears for actuating said lever mechanism, and means for driving the intermittent gears, said gears being arranged to 70 actuate the lever mechanism to actuate the rail key, wedge, and locking bar in pre-determined order in fastening and unfastening the bridge.

75 In testimony whereof, I have hereunto 80 set my hand.

DEMPSEY L. REEHL.
